PORTABLE INCANDESCENT LAMP

Edmund K. Sovatsky, Howard Beach, N.Y., assignor to
Tensor Electric Development Company, Inc., Brook-
lyn, N.Y., a corporation of New York

Filed Sept. 28, 1962, Ser. No. 71,912

Term of patent 14 years

(Cl. D48—20)

FIG. 1 is a side elevational view of a portable incandescent lamp showing my new design;

FIG. 2 is a top plan view thereof;

FIG. 3 is a left side elevational view with respect to FIG. 1;

FIG. 4 is a right side elevational view with respect to FIG. 1; and

FIG. 5 is a top plan view of the lamp base taken along line 5—5 of FIG. 3.

I claim:

The ornamental design for a portable incandescent lamp, as shown.
